B OFFENSIVE PLAYS

- 1. SINGLE
- 2. BASE ON BALLS
- 3. INFIELD HIT
- 4. STOLEN BASE
- 5. HIT BY PITCHED BALL
- 6. TWO BASE HIT
- 7. FIRST BASE ON ERROR
- 8. THREE BASE HIT
- 9. WILD PITCH
- 10. PASSED BALL
- 11. HOME RUN

* RUNNER ADVANCES TWO BASES.

C DEFENSIVE PLAYS

- 1. GROUNDED OUT
- 2. FLOWN OUT
- 3. FOULED OUT
- 4. STRUCK OUT
- 5. CROUCHED STEALING
- 6. SACRIFICE HIT
- 7. SACRIFICE FLY
- 8. HIT BY BATTED BALL
- 9. FIELDERS' CHOICE
- 10. FLOWN OUT AND RUNNER DOUBLED OFF BASE.
- 11. RUNNER FORCED AND BATTER DOUBLED AT FIRST.

THE OBJECT OF THIS CONTEST IS FOR THE CONTESTANTS TO FIGURE OUT BY ELIMINATION THE CORRECT OFFENSIVE OR DEFENSIVE PLAYS IN THE SIX SPACES DESIGNATED BY A (X). THE FIXED SUM TOTALING THE AMOUNT OF THE SIX PLAYS MAY BE GIVEN THE CONTESTANTS.

Inventor.
Emil S. Neuzil,

Atty's

UNITED STATES PATENT OFFICE.

EMIL S. NEUZIL, OF CHICAGO, ILLINOIS.

GAME OR PUZZLE.

Application filed April 6, 1925. Serial No. 20,883.

This invention relates to games or puzzles and more particularly to a contest such for instance as a base ball game.

One of the objects of the present invention is to provide a game or puzzle which has particular reference to base ball, but in which an unlimited number of contestants may take part.

Another object of the invention is to provide a game or contest in which the contestants are to figure out by elimination the correct offensive or defensive plays designated by the blind spaces.

A further object of the invention is to provide a base ball score sheet on which the plays are indicated with certain of the plays indicated by blind characters, which are to be filled in by the contestants.

A still further object of the invention is to provide an improved base ball contest in which the plays are divided into offensive and defensive plays, having corresponding symbols or numbers, which symbols or numbers may be placed opposite the names of the base ball players to indicate the play during each inning of the game.

A still further object of the invention is to provide a game or puzzle in which the official scorer holds the combination of blind numbers indicating the plays, but divulges the total of the combination of blind numbers to each contestant before the game is started.

These and other objects are accomplished in the manner hereinafter described and particularly pointed out in the appended claims.

Referring to the drawing, Fig. 1 illustrates a score sheet A which is distributed among the contestants for playing the game or solving the puzzle.

On this score sheet the two base ball clubs or teams consisting of nine men each are arranged in a column on the left hand margin of the sheet. For the purpose of illustration I have inserted the names of the Chicago Cubs base ball team and the names of the Pittsburgh base ball team, but it will of course be understood that any other teams may be substituted in lieu of those indicated in the drawing. The score sheet is blocked

off in the manner well known in base ball games in which the innings of the game are indicated by the numerals from 1 to 11 inclusive across the top of the score sheet. Just below the last named player of the last team, the Pittsburgh team, the totals of the runs of each base ball team are placed, with the total in the innings 3, 7 and 9 left blank for the purpose of which will hereinafter be discussed. In the lower part of the score sheet I have provided a guide in which I have arranged the plays of the games under two heads, B, offensive plays, and C, defensive plays. Under the list of offensive plays are No. 1, single; No. 3, base on balls; No. 5, in-field hit; No. 7, stolen base; No. 9, hit by pitched ball; No. 11, two base hits; No. 13, first base on error; No. 15, three base hits; No. 17, wild pitch; No. 19, passed ball, and No. 21, home run. Under the defensive plays the following are listed. No. 2, grounded out; No. 4, flied out; No. 6, fouled out; No. 8, struck out; No. 10, caught stealing; No. 12, sacrifice hit; No. 14, sacrifice fly; No. 16, hit by pitched ball; No. 18, fielder's choice; No. 20, flied out and runner doubled off base, and No. 22, runner forced and batter doubled at first.

Each of these plays are provided with a symbol or number which is inserted opposite the player's name and in the inning that the play is played. Opposite the word "No. 1, single" is an asterisk which indicates "runner advances two bases". By this is meant that if there is a player on first base and the batter gets a single, the player on first base advances two bases, or if the player is on second and the batter gets a single, the player on second reaches home, scoring a run.

On the score sheet illustrated in the drawing, the first player "Adams" under the first inning, No. 3, indicates that this player took his base on balls. The next, or second player, "Heathcote" made a sacrifice hit, as indicated by the numeral 12, the third and fourth players, "Grigsby" and "Miller", respectively, both flied out, as indicated by the numeral 4 following their name in inning No. 1. In other words, the "Cubs" team made no score on the first inning.

Under the "Pittsburgh" team, "Bigbee", the first player, made an infield hit, as indicated by the symbol or numeral 5 following his name in the first inning. The second player, Carey, was hit by a pitched ball, as indicated by the symbol or numeral 9, following his name in the first inning, thus leaving two men on base, one on first and one on second. The third man "Wright" flied out, as indicated by the numeral 4 following his name. The fourth man "Traynor" makes a two base hit, as indicated by the symbol or numeral 11 following his name in the first inning, thereby bringing "Bigbee" from second to home, and scoring a run, leaving "Carey" on third base and "Traynor" on second base. The fifth man "Barnhart" struck out, as indicated by the symbol or numeral 8 following his name in the first inning. The sixth man "Moore" grounded out, as indicated by the symbol or numeral 2 following his name in the first inning. This means that the "Pittsburgh" team made one run the first inning and the "Cubs" made no run.

In a similar manner the other innings may be gone over to indicate how the different teams score or failed to score.

The principal feature of my invention of playing this game is the insertion of blind plays in the innings 3, 7 and 9, which are indicated by an "X" in these innings. For example, the blind play "X" as indicated by D opposite the name of the player "Miller" in the third inning might be any one of the following offensive plays: No. 1, single; No. 3, base on balls; No. 5, in field hit; No. 7, stolen base; No. 9, hit by pitched ball; No. 11, two base hit; No. 13, first base on error; No. 15, three base hit, or No. 21, home run.

In other words, a choice of any one of the above symbols or numbers indicating the offensive play may be inserted in place of the blind number "X" in the third inning opposite the player "Miller". In the next blind number "X" opposite the player "Barnhart" in the third inning as indicated at E, any one of the following symbols or numerals indicating the offensive plays may be inserted. No. 1, single; No. 3, base on balls; No. 5, in field hit; No. 9, hit by pitched ball; No. 11, two base hit; No. 13, first base on error; No. 15, three base hit; and No. 21, home run. In the same manner as above indicated any symbol or numeral indicating any one of these plays may be inserted in place of the "X" as shown at E.

In a similar manner the four other blind numbers "X" in the innings 7 and 9 may be substituted for the symbol or numeral indicating the proper play to complete the score card. Each of these "X's" represent particular symbols or numbers held by the official scorer, indicating the correct play to be inserted for completing the score card. In other words, the first blind "X" may be any

one of several plays as previously described, but the official scorer retains one particular number or play for this particular inning and player, and in each of the other blind plays the official scorer has a particular number representing a certain play for completing the score card, although, of course, it would be possible to insert any number of plays and still complete the score card, but in order to win the game or the contest the particular symbol or number representing the particular play is held by the official scorer and is not divulged until all the score cards are turned in by the contestants. Under the heading Totals below the names of the players are the names of the teams "Cubs" and "Pittsburgh." In lines opposite these teams; that is, "Cubs" and "Pittsburgh," are numerals indicating the total runs scored during each inning by the players of the respective teams.

In playing the game I desire to also assist the contestants by having the official scorer supply the key number. That is, in this particular case to give the contestants the total sum of the number representing all the blind plays. In other words, there are six blind plays which may be inserted for completing the score card and the official scorer may say in playing this game that the total of these six blind plays is 51 and then it is up to the contestants to insert the proper combination of numbers representing the different plays for completing the score card.

While of course it may be of assistance to the contestants to supply the key number, it is not absolutely necessary and in place thereof the total runs of the opposing base ball teams may be given. For example, if the X-spaces were filled in in the innings 3, 7 and 9 correctly so that the total score would show the Cubs nine runs against the Pittsburgh score seven runs, the following numerals indicating the proper plays would have to be inserted in the X spaces. Miller in the third inning would be No. 1 single; O'Farrel, seventh inning No. 15, three base hit; Pittinger, ninth inning, No. 11, two base hit; Barnhardt, third inning, No. 11, two base hit; Morrison, seventh inning, No. 8, struck out; Carey, ninth inning, No. 5, in field hit. With these numbers inserted in the blank spaces indicating the proper play, the third inning would show the Cubs no score, with Pittsburgh one run. In the seventh inning the Cubs would score three runs, while the Pittsburghs did not score. In the ninth inning the Cubs scored two runs as against the Pittsburgh scoring two runs, making a total of nine for the Cubs and seven for the Pittsburgh team. In order to simplify and more clearly understand the manner in which these spaces are filled in the following diagrammatic arrangement of

the innings and teams as well as the players and the particular plays in corresponding numbers are arranged in column order:

Innings	1	2	3	4	5	6	7	8	9	Total
5 Cubs		0		3	2				9	
Pittsburgh		1		0	2				7	

Cubs.

X Miller	3rd inning	# 1	Single.
X O'Farrell	7th inning	# 15	Three base hit.
X Pittinger	9th inning	# 11	Two base hit.

10 X Barnhart	3rd inning	# 11	Two base hit.
X Morrison	7th inning	# 8	Struck out.
X Carey	9th inning	# 5	Infield hit.

From the above it will be seen that in order that the total runs of each of the teams may be given previously to the beginning of the contest it is necessary that the proper numeral indicating the proper play be inserted. This proper play or its corresponding numeral is secured from the guide under which is listed the offensive and defensive plays.

In making up this score card of course one might follow an official score card, or it is possible, of course, to make up a score card apart from any real game and in addition thereto more or less than six blind plays may be inserted throughout the game to increase the combination of numbers.

30 On the score card in different plays is a small symbol or numeral together with an inclined line which indicates a secondary play, such, for instance, as No. 7, stolen base, or No. 19, passed ball.

35 In arranging the offensive and defensive plays together as shown on the drawing at B and C with their corresponding symbols or numerals indicating each of these plays I have formed a guide by means of which the correct symbols or numerals are inserted for completing the plays in each inning of the game and for supplying the contestants with the proper symbol or numeral to be inserted in the blind space indicated by "X" on the score card.

It will of course be understood that while I have described in the above specification and illustrated in the drawings the manner in which my improved game or puzzle may be played by the use of numerals, other characters or symbols may be used without departing from the spirit of my invention.

While in the above specification I have described one embodiment of my invention as particularly adapted to the game of base ball, it will, of course, be understood that various other forms and modifications may be made and applied to games other than base ball and still be within the scope of my invention as defined in the following claims.

What I claim as my invention and desire to secure by Letters Patent is:

1. In a game, the combination of a score card having certain numerals thereon rep-

resenting plays and certain other characters representing unknown plays.

2. In a game, the combination of a score card having certain numerals thereon representing certain plays, and blank spaces arranged between certain of said numerals for the insertion of certain other numerals representing plays for completing the game. 70

3. In a game, the combination of a score card having certain numerals thereon representing plays, a guide associated with said score card having a number of plays corresponding with numerals on said score card, and spaces between certain of the numerals on said score card for the insertion of the 80 numeral representing the proper play for completing the game.

4. In a game comprising a score card having certain plays represented thereon, blank spaces between certain of said plays, and a 85 guide for indicating the play to be inserted in said blank spaces for correctly completing the score card.

5. In a baseball game comprising a score card having numerals representing a plurality of plays made by each player, a blank space between certain of said plays, and a guide consisting of a plurality of offensive and defensive plays, each of the plays on said guide having its respective number 90 whereby the proper number may be inserted in said blank spaces for completing the score card. 95

6. In a baseball game comprising a score card having two teams of nine players thereon and blocked off in innings, a plurality of numerals placed in the various innings opposite the names of the players representing different plays in a base ball game, certain of the plays between the numerals left blank whereby certain numerals may be inserted to complete the score card. 100

7. In a baseball game comprising a score card having two teams of nine players thereon and blocked off in innings, a plurality of numerals placed in the various innings opposite the names of the players representing different plays in a base ball game, certain of the plays between the numerals left blank, 110 a guide associated with the score card having numerals corresponding with the plays on said score card for aiding the contestant in inserting the proper number in the blank space corresponding to the correct play for completing the score card. 105

8. In a baseball game, the combination of a score card having characters representing plays made by each player, certain of said characters being blind, and a guide associated with said score card whereby the 115 proper character may be substituted for said blind character. 120

9. In a game or puzzle the combination of a score card having certain blank spaces thereon and a guide having symbols desig- 125

nating different plays of a baseball game whereby only certain of said symbols may be inserted in the blank spaces of said score card.

5 10. In a game or puzzle the combination of a score card having certain blank spaces thereon, a guide having symbols represent-

ing certain plays in a baseball game whereby certain symbols may be inserted in certain spaces on said score card. ¹⁰

In testimony whereof I have signed my name to this specification, on this 2nd day of April, A. D. 1925.

EMIL S. NEUZIL.
